UNITED STATES PATENT OFFICE.

FRANZ SCHOHAUS, OF LA PAZ, BOLIVIA.

NON-TELESCOPING RAILWAY ROLLING-STOCK.

1,234,809.

Specification of Letters Patent.

Patented July 31, 1917.

Application filed October 17, 1912. Serial No. 726,225.

To all whom it may concern:

Be it known that I, FRANZ SCHOHAUS, a citizen of the German Empire, and a resident of La Paz, Bolivia, have invented certain new and useful Improvements in Non-Telescoping Railway Rolling-Stock, of which the following is a specification.

The present invention relates to railway rolling stock and more particularly to non-telescoping railway cars or other vehicles. Its purpose is to prevent danger to life and limb of passengers in case of train collisions. While a number of devices of this general character are in existence, it is thought to be broadly new to provide a non-telescoping railway car, comprising a car body, pivoted on a vertical axis whereby the force of the collision, rotates the car body on this pivot so as to remove the car from the danger zone.

The invention, in a general way, comprises an ordinary truck platform resting upon a pair of auxiliary platform sections, to which the trucks are secured. The main platform is provided with a central bearing to receive a tubular pivot connected to the car body. The car body is located on the main platform and provided with two strong crank pins, which pass through suitable guide slots in the platform and engage the inner ends of the auxiliary platform sections. In case pressure is exerted against the outer ends of the auxiliary platform sections, the inner ends are brought nearer together, the crank pins are acted upon to rotate the car body on its pivot and the car body becomes displaced in a plane parallel to the plane of the platform truck and at an angle to its longitudinal axis.

For the purpose of normally resisting slight pressures such as might be caused by arranging the cars and making up the trains in the railroad yards or by starting and stopping the trains and normally forcing apart the auxiliary platform, a series of resilient members are arranged between the inner ends of the auxiliary platform sections in such a way that a normal pressure against the outer ends of the sections is taken up by these springs, without displacing the car bodies.

An important feature of the invention consists in the arrangement of a valve, operated by the displacement of the platform sections and admitting air to the air brake

system of the entire train, so that in case of a collision and a displacement of the car bodies, all the brakes of the entire train will be set and the train forced to stop.

The drawings illustrate the present invention in—

Fig. 1, is a perspective view of the two cars, displaced after a collision,

Fig. 2, a bottom view of the car,

Fig. 3, a cross section in the line 3—3 of Fig. 2,

Fig. 4, a perspective view of a car body,

Fig. 5, a bottom view of the platform, upon which the car body rests and

Fig. 6, a plan view of the under side of the sections of the auxiliary platform to which the trucks are connected, with certain parts omitted.

The car body 1, is of the ordinary construction of a passenger, Pullman or other car, or of a box or freight car, and is provided with a tubular pivot 2, located approximately at the intersection of the longitudinal and transversal axis of the car, said pivot 2 being provided with a collar 2^a secured thereto for holding the same in position.

Two strong crank pins 3, are secured to the bottom of the car body, for a purpose hereinafter to be particularly described. The car body may have rectangular ends or, if desired, the ends may be bevel edged. The car body rests upon the main platform 4 which is provided with two semi-circular slots or guideways 5, through which the crank pins 3 pass and are capable of sliding therein. The platform 4 is formed with two longitudinal flanges or guides 6, and with an opening 7, forming a bearing for the tubular pivot 2, of the car body. The ends of the platform 4 may also be rectangular or beveled, according to the construction of the car body.

Fig. 6 illustrates the sections 8 and 9 of the auxiliary platform which are constructed to slide along the guides or flanges 6 of the main platform 4. Formed integral with, or formed separately and secured to, each of the flanges 6, is a longitudinally extending plate 6^a, which plates act as guides for the sections 8 and 9 at each side thereof. The sections are arranged in one plane and below the platform 4, and suitably spaced apart and extend over the ends of the platform 4. The inner ends of the sections 8

and 9, are provided with the oppositely projecting bearings 10 and 11, for the crank pins 3, of the car body. Truck pivots 12 and 13, are provided about midway of the sections, and lugs 14 and 15 are arranged to limit the rotation of the trucks 16 and 17, upon which the sections 8 and 9, as well as the entire car structure, are supported.

Fig. 2 represents a bottom view of the invention, showing a cross bar 18, secured to a flange 18^a extending below from the section 8, which bar forms the support for a number of rods 19, rigidly secured to this bar 18 which, in turn, is fastened to the flange 18^a by means of suitable rivets. Each rod 19 is provided with a helical spring 20, and these springs are held under compression by means of a rod supporting bar 21, placed upon the free ends of the rods 19 and 20 slidable thereon. The bars 21 are held apart by a pair of separating members 22, which are located in the guides 6 of the platform 4.

A valve adapted to admit atmospheric pressure to the brake mechanism of the entire train, comprises two tubular members 23 and 24, one of which is secured to one of the bars 18 and the other to one of the bars 21. The tube 23 is provided with an opening 25 and the tube 24 with a similar opening not shown in the drawing, which are arranged to coincide on the displacements of one tube within the other and to admit air to the tube 24 and its connections, as hereinafter will more fully appear. The end of the platform sections 8 and 9, are provided with the usual buffers 26 and 27, under the pressure of the helical springs 28 and 29.

The principle of the invention is to be found in the operation of the sections 8 and 40 9, in connection with the crank pins 3 of the car body 1. If the sections are displaced and brought together in the longitudinal axis of a car, they cause a rotation of the crank pins 3, which glide in the guideways 45 5 of the platform 4, and swing the car body 1, on the pivot 2, into the position indicated in Fig. 1 of the drawing. This operation is normally resisted by the pressure of the springs 20 and becomes effective only, when the pressure exerted upon the sections is 50 greatly in excess of the resistance of the springs 20.

The operation of this invention consists in 55 causing a pressure of great force in the direction of the longitudinal axis of a train of cars such as may happen in a collision of two trains. This pressure, if only slight, will be taken up by the buffer springs 28 and 29, and have no effect whatsoever. Should 60 this pressure, however, be greatly in excess of the force of the buffer springs, and also in excess of the force of the springs 20, then the sections 8 and 9 are forced together, and 65 the crank pins 3, cause the swinging out of the car body, off the longitudinal axis of the

train, so as to prevent any danger to life and limb of the passengers that may result from the telescoping of the cars.

The opening in the tubular pivot 2 is arranged to receive all usual pipe or other connections, for supplying the car with heat, light or compressed air and also such other piping as may be necessary to control the air brake or other devices necessary for the security of a train. It will be noted that a displacement of the platform sections, which results in the compression of the springs 20, causes the tube 24 to which the hose or pipe of the air brake is connected, to be pushed into the tube 23, until the opening 25 coincides with the proper opening of the tube 24, whereby air is admitted to the pipe system and the air brake brought into operation to stop the entire train.

The inventor regards as his invention and discovery and desires to secure by Letters Patent of the United States, the following:

1. The combination with railway car trucks, of a truck platform supported by each truck, a main platform along which said truck platforms are slidable, and a car body pivotally mounted upon said main platform.

2. The combination with railway car trucks, of a truck platform supported by each truck, a main platform along which said truck platforms are slidable, a car body pivotally mounted upon said main platform, and means controlled by the sliding movement of said truck platforms for rotating 100 said car body.

3. The combination with railway car trucks, of a truck platform supported by each truck, a main platform along which said truck platforms are slidable, resilient means for controlling the sliding movement of said truck platforms, a car body pivotally mounted upon said main platform, and means controlled by the sliding movement of said truck platforms for rotating said car body.

4. The combination with a railway car truck, of a truck platform supported by said truck, a main platform along which said truck platform is slidable, said main platform being provided with a curved slot, a car-body pivotally mounted upon said main platform, a projection on said car-body adapted to traverse said slot, and means on said truck platform for causing said projection to traverse said slot to rotate said car-body.

5. The combination with railway car trucks, of a truck platform supported by each truck, a main platform provided with guides along which said truck platforms are slidable, said main platform being also provided with a plurality of curved slots, a car-body pivotally mounted upon said main platform, a plurality of projections secured 130

to said car-body and adapted to traverse said slots, means on said truck platforms for moving said projections to traverse said slots, and means normally withholding from operation said moving means.

In witness whereof the inventor has hereunto set his hand in the presence of two sub-

scribing witnesses, at La Paz, Bolivia, this 10th day of Sept., 1912.

FRANZ SCHOHAUS.

In presence of—

FREDK. SCHONER,
JOSÉ E. PONTE.
